PURIFICATION OF NAPHTHENIC ACIDS

Frederick J. Ewing, Pasadena, Calif., assignor to
Union Oil Company of California, Los Angeles,
Calif., a corporation of California

No Drawing. Application October 2, 1933,
Serial No. 691,895

18 Claims. (Cl. 260—108)

This invention relates to the purification of naphthenic acids. A primary object thereof is to present a simple and thoroughly satisfactory process for effecting the permanent removal of substantially all of the dark coloration and pungent odor which usually accompany these acids.

Naphthenic acids, such as might be obtained from the alkali wastes arising during the refining of petroleum or shale oil fractions, constitute a complex mixture of acidic compounds containing principally carbon, hydrogen and oxygen. They range from comparatively low boiling liquids to compounds which are solid or semi-solid at ordinary temperatures. Their viscosity in most instances is directly proportional to the viscosity of the hydrocarbon fractions in which they were originally present. The acidic character of the naphthenic acids is believed to be due to the presence of one or more carboxyl (COOH) groups.

Naphthenic acids, as originally obtained from the alkaline refining wastes of various hydrocarbon fractions including those stated above, possess a dark red to black color and this color subsists whether or not the acids be substantially free from associated phenolic and hydrocarbon materials. When such acids are distilled, which may or may not be performed under reduced pressure, the overhead product is substantially colorless but it rapidly reverts to a dark amber or black color on standing, thereby rendering the acids unfit for use in many instances where a light colored product is to be used. Therefore, it is desirable to obtain colorless naphthenic acids which do not darken on standing even over a prolonged period of time and which also possess a bland to sweet odor.

I have discovered that such a decolorization and deodorization of naphthenic acids may be brought about by contacting the crude or semi-refined acids with certain normally gaseous oxidizing agents. The above treatment may be carried out in the presence of small amounts of non-volatile catalysts such as for instance some of the well known inorganic oxides; however, excellent results have been obtained in many cases where these catalysts were omitted. The gaseous oxidizing agent is preferably introduced as a slow but steady stream, directly into the charge of naphthenic acids during the distillation thereof. By operating in this manner, it is found that not only does the overhead product possess all of the desired characteristics as to odor and color but that these properties are retained even on standing for considerable periods of time.

The normally gaseous oxidizing agents which

I propose to use in my invention are gases containing oxygen or which are capable of generating oxygen under the conditions which prevail during the deodorization and decolorization of the naphthenic acids to be hereinafter more fully described. Typical examples of gases which may be employed in my process are: Air, nitrogen peroxide, mixtures of air and nitrogen peroxide, and mixtures of air and hydrocarbon gases or mixtures of oxygen and hydrocarbon gases. When mixtures of oxygen and hydrocarbon gases are employed, the amount of oxygen present should preferably be less than one-half by volume of the total amount of gas used.

The catalysts which may be used in conjunction with the gaseous oxidizing agents set out above are cupric oxide, manganese dioxide, mercuric oxide, ferric oxide, litharge, etc. While these oxides are themselves capable of deodorizing and decolorizing naphthenic acids as has been disclosed and claimed in my co-pending application, Serial No. 684,929, they are added in such small amounts that they cannot by themselves be considered to be responsible for the purification of the naphthenic acids. The addition of any of the above-named catalysts appears to bring about a reduction in the time necessary for contact between the acids and the gaseous oxidizing agent, and therefore may be said to increase the efficiency of the latter. Only in the case of very dark colored naphthenic acids has any material improvement in the color of the finished product been observed when these catalysts were added.

The decolorization and deodorization of the crude or semi-refined naphthenic acids according to my invention is carried out in the absence of any substantial amounts of water and thus avoids the emulsification difficulties which arise on treating naphthenic acids with aqueous solutions of oxidizing agents such as has been done in the past. Moreover, the introduction of the gaseous oxidizing agent into the still charge does not only agitate the mass to be treated, but also tends to lower the temperature necessary to distill the naphthenic acids overhead and in so doing eliminates any substantial danger of thermal decomposition during the distillation stage. As the treating agents used in this invention are gaseous substances the necessity of eliminating any of them from the purified product has been entirely excluded.

The finished product, obtained according to my invention, is substantially free from phenolic material which is believed to be due to the treat-

ment of the crude or semi-refined acids with an oxidizing agent at elevated temperatures; however, I do not wish to be limited by any such theory. It is however, a known fact that the absence of phenols in naphthenic acid mixtures accounts for high acid numbers of the purified acids.

In practice, the crude naphthenic acids which have been preferably freed from the major fraction of the phenolic material are distilled in the presence of a small amount of dry steam or hydrocarbon gas in order to eliminate the admixed asphaltic and carbonaceous materials. The partially purified naphthenic acids are then redistilled while introducing a current of air or of any of the gaseous oxidizing agents previously enumerated. While this preliminary distillation in the presence of steam or hydrocarbon gas has been found to be helpful in a number of cases, especially where excessive temperatures are to be avoided, it is not considered to be an essential step in the obtainment of the desired results.

Therefore, my invention may be said to reside in a process for deodorizing and decolorizing naphthenic acids which comprises treatment during distillation or heating thereof, with gases containing oxygen or capable of generating oxygen under the conditions prevailing during the aforesaid deodorization and decolorization. My invention also extends to the employment of small amounts of inorganic oxide catalysts in conjunction with the aforesaid gaseous oxidation agents. In a more limited fashion, my invention relates to the deodorization and decolorization of naphthenic acids by introducing a suitable quantity of air into naphthenic acids while the same are being heated or distilled for the purpose of obtaining a product of a highly stable color and a bland odor.

Considering the process in greater detail, a caustic liquor, such as might be obtained by treating crude kerosene or a liquid sulphur dioxide extract thereof, with sodium hydroxide, is neutralized in such a manner that it is only slightly basic toward phenolphthalein. By so operating, the naphthenic acids, in contrast to the phenols, are not liberated from their alkali metal salt but remain as sodium naphthenates. The resulting mixture of sodium naphthenates, phenols, and admixed hydrocarbons is then steam distilled. The sodium naphthenates remain behind in the still and when dissolved in water and treated with sulphuric acid, produce naphthenic acids which contain only very small amounts of phenols and admixed hydrocarbons. These crude naphthenic acids are of a poor color and contain considerable amounts of insoluble carbonaceous material. They are preferably subjected to a preliminary distillation in the presence of dry steam or some of the normally gaseous hydrocarbons such as ethane or methane, to remove the above-mentioned undesirable fractions. The effect of the introduction of the steam or hydrocarbon gas is to lower the temperature necessary to distil the mixture and thereby avoid any undue cracking and eliminate the necessity of carrying out the distillation under reduced pressure.

The overhead product when first condensed is a clear light yellow liquid but acquires a deep red color so rapidly that in a few hours layers greater than an inch in depth are virtually opaque. Small amounts of water usually come over during the initial stages of the distillation and may

be removed by a simple settling or centrifuging process.

The "semi-refined" naphthenic acids which were condensed as an overhead product are subsequently introduced into a still provided with any suitable means for introducing the gaseous oxidation agent during the distillation of the naphthenic acid still charge. If desired, small amounts of inorganic oxides such as cupric oxide may be added to the aforesaid acids before the heating or distillation and the introduction of the gas is commenced. In general, 0.001% to 0.1% of cupric oxide or any of the other inorganic oxides previously enumerated have been found to be sufficient. Excellent results have however been obtained where these catalysts were omitted as may be seen from Example 1 hereinafter described. The mixture is then distilled under atmospheric pressure until substantially all of the purified naphthenic acids are removed as an overhead product. They are found to be of an excellent color and possess a bland to sweet odor and do not darken on standing even for a period of time as long as six months. In addition, they possess an increased acid number and saponification number and a decreased sulphur content in comparison with the crude product.

Example 1

A mixture of crude naphthenic acids derived from the caustic liquor obtained in the refining of a kerosene fraction and which has been substantially freed from admixed phenols by careful acidification, steam distillation and acidification of the sodium naphthenate residue as previously described, had the following properties:

Acid number	283 mgs. KOH per gram of substance
Saponification number	283 mgs. KOH per gram of substance
Specific gravity	0.97
Color	Dark brown
Sulphur content	0.21%
Boiling range	480-580° F.
Sediment	1 to 2%

These acids were subsequently distilled in the presence of small amounts of dry steam or hydrocarbon gas which was introduced into the still during the distillation. The semi-refined naphthenic acids which were condensed as an overhead product had the following properties:

Acid number	284 mgs. KOH per gram of substance
Saponification number	286 mgs. KOH per gram of substance
Specific gravity	0.95
Sulphur content	0.12%
Boiling range	480-575° F.
Sediment	None

The naphthenic acids condensed as an overhead product had a clear straw-like color which deepened into a dark red after standing for only a few hours.

Three hundred and fifty (350) cubic centimeters of these acids were introduced into a still provided with a pipe for introducing a slow current of air into the mass during distillation.

The boiling point range decreased from 480 to 530° F. for the semi-refined naphthenic acids to

475° F. to 565° F. for the finished product which had the following characteristics:

2. A process according to claim 1 in which the oxygen-containing gaseous oxidation agent is introduced during distillation of the naphthenic acids.

5. A process as defined in claim 1 in which the contacting of the naphthenic acids with the gaseous oxidation agents is carried out in the presence of a metal oxide oxidation catalyst capable of increasing the efficient action of the aforesaid gaseous oxidation agents.

3. A process as defined in claim 1 in which the contacting of the naphthenic acids with the gaseous oxidation agents is carried out in the presence of metal oxide catalysts capable of increasing the efficient action of the aforesaid gaseous oxidation agents.

4. A process as defined in claim 1 in which the contacting of the naphthenic acids with the gaseous oxidation agents is carried out in the presence of metal oxide catalysts capable of increasing the efficient action of the aforesaid gaseous oxidation agents.

5. A process as defined in claim 1 in which the total amount of the gaseous oxidation agents employed is from 10 to 50 times by volume that of the liquid naphthenic acids.

6. In a process for deodorizing and decolorizing naphthenic acids, the step which comprises contacting said acids at temperatures from 475° F. to 565° F. with air.

7. A process according to claim 6 in which the air is introduced during distillation of the naphthenic acids.

8. A process as defined in claim 6 in which the contacting of the naphthenic acids with air is carried out in the presence of metal oxide catalysts capable of increasing the efficient action thereof.

9. In a process for deodorizing and decolorizing naphthenic acids, the step which comprises contacting said acids at elevated temperatures with nitrogen peroxide.

10. In a process for deodorizing and decolorizing naphthenic acids, the step which comprises contacting said acids at elevated temperatures with mixtures of air and nitrogen peroxide.

11. A process for deodorizing and decolorizing naphthenic acids which comprises distilling a mixture of crude naphthenic acids to remove the admixed carbonaceous materials present therein and redistilling the overhead product so obtained in the presence of an oxygen containing gaseous oxidation agent whereby there is imparted a light color of high stability and a bland odor to the aforesaid naphthenic acids.

12. A process for deodorizing and decolorizing naphthenic acids according to claim 11, in which the oxidation agent used is air.

13. A process for deodorizing and decolorizing naphthenic acids according to claim 11 in which the oxidation agent used is a mixture of air and nitrogen peroxide.

14. A process as defined in claim 11 in which the redistillation of the naphthenic acids with the gaseous oxidation agents is carried out in the presence of metal oxide oxidation catalysts capable of increasing the efficient action of the aforesaid gaseous oxidation agents.

15. A process for obtaining naphthenic acids of a high color stability and a bland odor which comprises extracting a petroleum fraction with alkali, acid treating the resulting extract in such a manner that only the phenols admixed with the alkali salts of the naphthenic acids are liberated, distilling the phenols overhead, liberating the free crude naphthenic acids from the alkali naphthenates remaining in the still after the said distillation for the removal of the phenols has been completed, distilling the liberated naphthenic acids to remove the admixed car-
